UNITED STATES PATENT OFFICE.

JOHN V. B. CARTER, OF DETROIT, MICHIGAN, ASSIGNOR TO DETROIT STOVE WORKS, OF SAME PLACE.

DESIGN FOR A HEATING-STOVE.

Specification forming part of Design No. 6,704, dated June 17, 1873; application filed May 17, 1873.

To all whom it may concern:

Be it known that I, JOHN V. B. CARTER, of Detroit, in the county of Wayne and State of Michigan, have invented a Design for a Stove, of which the following is a specification:

The nature of my design is fully represented in the accompanying photographic illustration, to which reference is hereby made.

A represents the base of my stove, provided with the ash-door and draft-register, circular in form and ornamented as shown. Surmounting the base is a fluted fire-pot, B. C is a combustion-chamber, of sheet metal, mounted on the fire-pot, with a wide opening extending from top to bottom, nearly closed with the double doors D D'. The borders of the doors are plain bevel-edge moldings studded with

simulated bolt-heads. E is the cap of the stove, its rim being a molding of the same style as that of the base-ring, and from its center rises an urn of the form shown.

The main door-panel is ornamented with a shield of the design shown; the upper door exhibits the name of the stove, while the general design of the stove is to produce a massive but chaste effect, devoid of superfluous ornamentation.

What I claim as my invention is—

A design for a stove, substantially as herein described and shown.

JOHN V. B. CARTER.
